WINDOW MECHANISM

Frank E. Zick, Dearborn, Mich., assignor of one-half to Charles R. Emery, Dearborn, Mich.

Application May 13, 1935, Serial No. 21,140

21 Claims. (Cl. 189—76)

My invention relates to improvements in window mechanisms adapted for the use with either panes of glass or screens, and the objects of my improvements are, first, to provide a window mechanism that can be used as a storm window in conjunction with the regular or conventional windows of a building; second, to provide a window mechanism that can be used as a storm window in conjunction with the regular or conventional windows of a building and at the same time are adapted to have the panes of glass therein readily removed and replaced by screen members during the warmer seasons of the year; third, to provide a window frame construction that will adjustably fit various sizes of window construction; fourth, to provide a window frame construction adapted to form a weather tight construction for holding both panes of glass and screen members; fifth, to provide a window construction provided with readily removable panes of glass having means for protecting the glass when stored during the period of removal from the window construction; sixth, to provide a window construction adjustable in longitudinal and transverse directions; seventh, to provide a window construction provided with a pair of frame assemblies having their adjacent frame portions contacting with an interlocking and overlapping construction; eighth, to provide a window mechanism having a frame construction provided with members for locking the frame construction longitudinally in the window frame; ninth, to provide a window mechanism having a frame construction provided with means for engaging the sides of the window frame to position said frame construction longitudinally of the window frame; tenth, to provide a window mechanism having a frame construction having means for automatically expanding said frame construction to engage various sizes of window frames; eleventh, to provide a window mechanism provided with channel or guide portions adapted to form a weather strip member when assembled in conjunction with a conventional window of a building by closing the crack or gap between the window mechanism and the window frame of the building when assembled therein; twelfth, to provide a window mechanism having frame members provided with U-shaped peripheral housings extending therearound and adapted to clamp and maintain glass or screen members within the open sides of the peripheral housings; thirteenth, to provide a window mechanism having peripheral frame members formed with U-shaped housings, the flanges of which are resilient to act as clamp members for holding a

glass or screen member; fourteenth, to provide a window mechanism having a frame member constructed with resilient flanges adapted to actuate resilient packing material supported thereon to engage and clamp glass or screen members; fifteenth, to provide window screen or glass members with a U-shaped protective member extending around and enclosing their peripheral edges; sixteenth, to provide a window mechanism having guide members provided with openings adapted to be engaged by plunger members movably mounted in window frame assemblies slidably mounted in the guide members for retaining the frame assemblies in their operative positions in the guide members; seventeenth, to provide a window mechanism having a pair of frame assemblies with adjacent and interlocking housings having offset portions to provide the interlocking engagement; eighteenth, to provide a window mechanism having a frame assembly constructed with one of its sides forming a hollow housing adapted to support plunger mechanism for locking the frame assembly in its operative position in the window mechanism; and nineteenth, to provide a window frame assembly with telescopically engaging housings, one of which is provided with a slot in its wall portion for receiving a clamping member mounted on the other of the housings.

I attain these objects by the mechanism illustrated in the accompanying drawings, in which:

Figure 1 is a view of my window mechanism installed in conjunction with a conventional window of a building, said view being taken from the inside of the conventional window, said conventional window being partially broken away to disclose the inside of my window mechanism, one of the sash or frame members, namely the lower one therein, being disclosed as supporting a pane of glass therein, the other or upper sash or frame member being disclosed as supporting a screen member therein; Fig. 2, a sectional view of the window mechanism disclosed in Fig. 1, said sectional view being taken on the line 2—2, Fig. 1; Fig. 3, a rear view of the upper sash or frame member disclosed as having been removed from the window mechanism assembly; Fig. 4, a sectional view through the upper portion of the window sash or frame member disclosed in Fig. 3, said sectional view being taken on the line 4—4, Fig. 3, said sectional view being drawn to a larger scale than that of Fig. 3; Fig. 5, a sectional view through the lower portion of the window sash or frame construction as disclosed

in Fig. 3, said sectional view being taken on the line 5—5, Fig. 3, said sectional view being drawn to a larger scale than that of Fig. 3; Fig. 6, a sectional view of the window sash or frame construction disclosed in assembly with the channel or guide members which position same in the conventional window mechanism of a building, said sectional view being taken on the line 6—6, Fig. 5; Fig. 7, a partial sectional view of the sash or frame member disclosed in Fig. 3, said sectional view being taken on the line 1—7, Fig. 3; Fig. 8, a partial side view of the sash or frame construction, together with the partial screen member supported therein; Fig. 9, a side view of the partial screen member in section; Fig. 10, a partial side view of one of the screen members disclosing the edge or frame portion thereof assembled in conjunction with a corner of the screen; Fig. 11, a partial view of one of the panes of glass used in my window mechanism, said view disclosing the means for protecting the edge of the pane of glass, said means being disclosed as applied to a corner of the pane of glass; Fig. 12, a top view disclosing one of the finger or handle members assembled to a portion of one of the sash or frame members; Fig. 13, a plan view of one of the plunger or locking members; Fig. 14, a side view of the plunger or locking member disclosed in Fig. 13; and Fig. 15, an end view of the plunger or locking member disclosed in Fig. 14.

Similar numerals refer to similar parts throughout the several views.

The sash or frame construction which encloses and supports the panes of glass or the screen members in my invention are formed with upper and lower sash or frame assemblies, Fig. 3 disclosing the upper and lower sash or frame assembly A which comprises the end members 1 and 2 together with the side members 3 and 4, said sash or frame assembly A further comprising the lower frame assembly B, said side members 3 and 4 being disclosed as having been adjusted to their innermost positions relative to the side portions 16 and 17 of the end members 1 and 2. The end member 1 is constructed with the channel or U-shaped structure or housing having the side flanges 5 and 6 which are offset at 7 so that said side flanges 5 and 6 will telescopically mount and slide within the side flanges 8 and 9 of the end member 2.

It is to be noted that the side flanges 8 and 9 of the end frame member 1 are each provided with the bent portions 15 which are brought together to form a relatively small space or opening therebetween for receiving the pane of glass or the glass assembly 11 or the screen assembly 12 therein, thus providing an inwardly facing open side of U-shaped housing, the portions 15 together with the flanges 5 and 6 possessing resilient characteristics tending to close the packing members 13 to further resiliently grip and contact the glass assembly 11 or the screen assembly 12 as the case may be in clamped positions, the packing or resilient members 13 being suitably secured to the inside surfaces of the side flanges 5 and 6 adjacent the inside of the bent portions 15 and the inner end of the surfaces of the open side of the U shaped housing.

The packing or resilient material 13 thus resiliently clamps and positions the glass assembly 11 or the screen assembly 12 in their positions in the frame assembly 1, the thicknesses of the packing or resilient material 13 being sufficient to allow the bent portions 15 to slidably clear or

barely contact the sides of the glass assembly 11 or the screen assembly 12.

It is to be noted that the bent portions 15 are each further extended to form the overlapping flanges 14 which extend around the outside of the extreme inner edges or ends of the bent portions 10 of the side flanges 5 and 6, the overlapping flanges 14 thus tending to maintain the frame members 1 and 2 in their proper positions relative to a plane extending in a transverse direction, relative to the plane of telescopic movement of the end members 1 and 2, the bent portions 15 slidably and telescopically moving between the overlapping flanges 14 and the bent portions 16 in the adjusting or telescopic movement of the frame members 1 and 2.

It is to be noted that the end frame members 1 and 2 will be further provided with the side portions or housings 16 and 17 which are suitably secured as by welding, soldering, or similar means to the end frame members 1 and 2, said end frame and said side portions or members being joined together as at their corners, as indicated by the diagonal lines 18.

In a similar way the side members 3 and 4 will be provided with similar side flanges 5 and 6 having the bent portions 15 which will be offset as at 19 to allow the side flanges 5 and 6, together with the bent portions 15, to be telescopically mounted and adjustably slid within the side flanges 8 and 9 of the side portions 16 and 17 of the end frame members 1 and 2, the side portions 3 and 4 also being further provided with the packing or resilient material 13 in a similar manner to that disclosed relative to the end frame members 1 and 2, in Figs. 3 and 4.

It is to be understood that the packing or resilient material 13 will be provided with sufficient length in the various side end members of the frame constructions, together with suitable thicknesses so that the respective end and side members may telescopically move without interference with the packing materials 13 when secured and mounted in the end frame and side members and their associated members with which they are telescopically mounted.

The clip or handle members 20 are secured to the end members 1 and 2 by the rivets 21, the clip or handle members each being provided with the curved flange 22 to provide a finger or hand hold for moving the end members 1 and 2 toward one another to provide a lesser over all width to the upper sash or frame assembly A than the upper sash or frame assembly A has been when assembled in conjunction with the conventional window opening structure as disclosed in Fig. 1, the movement of the members 1 and 2 toward one another when compressed by the hands of the operator against the flange portions 22 constituting an adjustable movement of the end members 1 and 2 to enable the upper frame assembly A to be moved and inserted between the channel or guide members 23 which are suitably secured to the side frame members 24 of the conventional window construction as disclosed in Figs. 1 and 2, the channel or guide members 23 extending longitudinally at the sides only of the window construction.

The clip or handle members 20 are each provided with the extension portion 36 which provides means for supporting and positioning the springs 37 between the flange portions 22, the extensions 36 extending within the coils of the springs 37, said springs 37 exerting a thrust outwardly against the flanges 32 to always auto- 75

matically force and expand the end members 1 and 2 outwardly to adjustably fit any reasonable tolerances in the frame construction of conventional windows of different sizes.

5 The channel or guide members 23 are preferably formed to provide the pair of channels 25 and 25A which are spaced by the portion 26 extending therebetween. The inner ends of the channel or guide members 23 are provided with 10 the flanges 27 which are folded over and carried outwardly to a position where its edge is in a position adjacent the inner surface of the frame members 24. The outer portion of the channel or guide members 23 are provided with the folded 15 or convoluted portion 28 which is extended to form the flange 29 which extends past and covers the outer edge 30 of the frame member 24, thus providing a weather strip construction which will exclude cold air, etc., from passing between the 20 contacting surfaces of the guide or channel member 23 and the inside surface of the frame member 24.

The channel or guide members 23 are secured to the frame member 24 by a plurality of screws 25 31 which extend through suitable openings in the channel or guide members 23 and engage the frame members 24.

It is to be noted that the side members 3 and 4, after they have been slidably moved relative 30 to the side portions or members 16 and 17 of the end members 1 and 2, may be locked in their adjusted positions by the screw 32 which extends through the slots 33 in the side members 16 and 17 and engage the telescoped flanges of the 35 members 3 and 4, the side flanges of said members 3 and 4 being formed, if desired, with the flange or displaced portion 34 to provide the boss in which the threads for engaging the screws 32 are located, the screws 32 being provided with 40 the knurled head or handle portion 35 to enable the screws 32 to be loosened so that the members 3 and 4 may be slidably and telescopically operated relative to the side portions 16 and 17 and to provide adjustable movement so that the upper 45 frame assembly A may be accommodated to windows to provide the necessary lengths when the upper frame assembly A has been adjusted to fit the conventional window frame of the window opening in which the channel or guide members 50 23 have been assembled, the screws 32 being tightened by means of the head or handle portions 35 to hold the side members 3 and 4 in their proper assembled positions relative to their side portions 16 and 17 of the end members 1 and 2. Also the flanges 8 and 9 of the end portions 55 1 and 2 may be extended to form overlapping edges 14 in the side members 1 and 2, as disclosed in Fig. 3, to engage the bent portions 10 of the flanges 5 and 6 of the side portions 3 and 4 to further position the side portions 60 3 and 4 transversely relative to the members 1 and 2.

After the glass assembly 11 or the screen assembly 12 has been installed in the upper frame assembly A, the lower side of the upper frame assembly A is closed by the lower frame assembly B.

The frame assembly B comprises a sash portion 38 which is provided with the offset portion 70 39 having the chamber 40 therein, the offset portion 39 extending toward and being adapted to engage a like offset portion 41 on the lower sash or frame assembly B of the upper frame assembly A.

75 It is to be noted that the frame member 38

is provided with the side flanges 42 and 43 which are extended to form the bent portions 44 and 45 in a similar manner to the side flanges 5 and 6 of the members 1, 2, 3 and 4 of the upper frame or sash assembly A.

The packing or resilient materials 46 is secured to the side flanges 42 and 43 in a similar manner to the packing materials 13, as above described. The frame member 38 is thus adapted to enclose the lower edge of the glass assembly 11 or the screen assembly 12, when assembled in the upper frame assembly A, the flanges 42 and 43 being adapted to be entered between the end portions of the flanges 5 and 6 of the side members 3 and 4, the frame or sash assembly B thus being 15 adapted to be entirely removed from the side members 3 and 4 of the upper frame assembly A to allow for the insertion of the glass assembly 11 or the screen assembly 12 as desired.

After the glass assembly 11 or the screen assembly 12 has been inserted within the upper sash or frame assembly A, the frame assembly B is telescopically mounted in position within and between the end portions of the side members 3 and 4 and to lock the frame assembly B against 20 movement longitudinally of the window opening and to further retain the sash or frame assembly A in an assembled position in the upper part of the guide or channel members 23, I provide the plungers 47 which are slidably mounted in the 25 chambers 40 and between the side walls of the frame members, such as 38, the plungers 47 being of sufficient width to extend adjacent the side surfaces of the offset portions 39 or 41.

The plungers 47 are provided with the studs 48 which are threadably secured in the holes 47A of the plungers 47, the studs 48 being provided with the handle portions 49 to facilitate the slidable movement of the plungers 47, the handle portions 49 being further constructed as a nut and 30 threadably engaging the stud 48 to permit clamping the plungers 47 in their engaged or disengaged position relative to the frame member 24 of the conventional window opening structure. The studs 48 extend throughout the slots 50 in 45 the outer walls of the frame members 38. The plungers 47 are each provided with the shouldered end 51 which may be provided with the angular sides 52, the shouldered portion 51 being adapted to enter and engage the holes 53 which are provided in the frame member 54 of the conventional window opening structure.

The plungers 47 are thus adapted for slidable movement in the frame member 38 so that the shouldered portions 51 may be entered within and 55 removed from the holes 53.

When the shouldered portions 51 are entered within and engage the holes 53, the frame assembly B is prevented from moving longitudinally of the frame member 24 of the window construction. This further positions and retains the sash or frame assembly A in its operating position, which in Figs. 1 and 2 is disclosed as being at the upper portion of the window opening of the building.

It also will be noted that the plungers 47 will be provided with the secondary plates 55 which may be secured to the main plate or portion of the plungers 47 as by welding, soldering, or similar means, the secondary plates 55 each having a width sufficient to allow them to be positioned in and slidably engage the side surfaces of the flange portions 42 and 43 of the members, such as 38, the secondary plates 55 having a shorter length than said main portions of the plungers 47 so that 75

their outer end surfaces may contact the inside surfaces of the channel or guide portions 24 and 25 when the plungers 47 are locked in their engaging positions with the holes 53, thus tending 5 to retain and maintain the frame members 3 and 4 outwardly in positions of close contact or engagement with the inside surfaces of the channel portions 25 and 25A of the guide members 23.

It is to be noted that the frame assembly A is 10 thus mounted in the channel portions 25 of the guide members 23 and at the upper portion of the window opening in the building while the frame assembly C is mounted within the channel portions 24 of the guide members 23 and at the lower 15 portion of the window opening in the building, as disclosed in Figs. 1 and 2, the frame assembly C being substantially identical with the frame assembly A but being assembled in a reverse position so that its frame assembly D, which is 20 constructed in a similar manner to the frame assembly B, will be inverted relative to its associated frame assembly, the offset portions 39 and 41 being positioned one above the other so that said offset portions 39 and 41 overlap and engage, as 25 disclosed in Fig. 5, the general construction of both of the frame assemblies B and D also being similar.

It is to be noted that the glass assembly 11 will 30 be provided with a protective and reinforcing member 56 around its peripheral edges, said protective and reinforcing material being suitably joined at its corners as disclosed at 57 in Fig. 11, the protective and reinforcing material 56 being preferably constructed of fabric, tape or similar 35 material which is secured to the pane of glass by adhesive or similar means.

The protective or reinforcing material 56 will 40 permit the panes of glass 11 to be removed from the frame assemblies of my invention during the warmer months when my window construction is not needed for use as a storm window for protection against cold weather, etc., the glass assembly 11 thus being possible of storage and handling without danger of injury or chipping at 45 its peripheral edges, the reinforcing or protective material 56 further enabling the panes of glass 11 to be stored adjacent one another without danger of breakage, etc.

It is also to be noted that the screen assembly 50 12, which may be used in my window mechanism during the warmer months of the year, is also provided with the protective and reinforcing frame portion 58 which extends around and encloses the peripheral edges of the screen member 55 12, said protective and reinforcing frame portion 58 being joined at their corners as disclosed at 59 in Fig. 11, the protective or reinforcing frame member 58 being preferably made of light weight and thin material such as pressed steel, aluminum, or similar material, which may be secured to the screen 12 as by welding, soldering, or similar means.

In order to further secure the frame assemblies 65 B and D in engagement with the side members 3 and 4 of the frame assemblies A and C, the frame members 38 may be provided with the portions 60 60 which may be formed by displacing a portion of the side wall of the frame 38 to provide increased stock for threadably engaging 70 the screws 61, the screws 61 extending through the slots 61A in one of the side walls of the flanges 6 of the frame members 3 and 4 of the frame assemblies A and C, thus providing further and positive means, if desired, for securing the 75 frame 38 in its assembled position relative to

the remaining portions of the frame assemblies A and C.

Figs. 1 and 2 disclose a pair of conventional window frame assemblies 62 and 63 in which are suitably secured the panes of glass 64 and 65, the 5 window assemblies 62 and 63 being mounted conventionally in the channel portions of the window frame members 24 by the members 24A, said frame members 24 being mounted in conjunction with the window ledge 66 together with the apron 10 or facing member 67 which is secured to the lower member 68 of the conventional window construction, the upper frame member being indicated at 69 and having the front facing member 70 which is also joined to the side frame members 24. The 15 complete conventional window construction is disclosed as being mounted within a building constructed of bricks 71.

It is to be noted that my window mechanism is adapted for use not only with conventional 20 window construction, as used in buildings constructed of brick, but is equally adapted to be used with conventional window construction in frame buildings and is further adapted for use in such 25 members as doors, etc., in which it may be desired to alternatively install window or screen members according to the seasons of the year.

In operation the guide or channel members 23 are secured in position to the longitudinal or vertical sides of the frame members 24 and then the 30 frame assembly A is collapsed by grasping the flange portions 22 of the clips or handles 20 with the fingers of the hand sufficiently to allow the over all width of the frame assembly A to be inserted between the minimum inside distance 35 between the minimum inside surfaces of the guide members 23 and then with the frame assembly A opposite one of the channel portions 24 or 25, the pressure of the fingers of the hands on the clips or handles 20 is released which allows the springs 40 37 to expand the end members 1 and 2 outwardly and sidewardly so that the side portions 16 and 17, together with the end members 1 and 2, and the side members 3 and 4 will be moved to and in close contact with the inside surfaces of the 45 guide or channel member 23 in which the frame assembly is to be operatively assembled.

The end members 1 and 2 are now forced upwardly in close contact with the upper surface of the frame member 68, as disclosed in Fig. 2, 50 then with the nuts 35 loosened, the side members 3 and 4 may be adjustably moved relative to the end members 1 and 2 so that they will fit substantially through one half the length of the window, the ability to move the end members 1 and 55 2, together with the members 3 and 4, of each of the frame assemblies A and C rendering it possible to make the frame assemblies A and C adjustably fit tightly around their peripheral edges in the inside channel and guide members 60 23 even though there are variations and tolerances between various windows, thus enabling my window mechanism to be produced in quantities and with interchangeable features rendering it 65 easily installed in various windows with different tolerances or dimensions and resultant discrepancies in the surfaces with which my window mechanism is associated and installed.

After the frame assembly A has been fitted to the inside surface at the top of the window structure, the glass assembly 11 is inserted between the flanges of the side members 3 and 4 and slidably moved upwardly to the position as disclosed in Fig. 3, with its peripheral edges, together with the reinforcing and protective materials there- 75

5 around, free of contact with the inside surface of the flanges of the frame assembly, the glass assembly 11 being resiliently contacted and clamped by the packing materials 13 due to the resilient characteristics of the inside flanges of the various members comprised by the frame assembly A.

10 The frame assembly B is now ready for installation and may be inserted between the end portions of side flanges of the members 3 and 4 so that the lower edge of the glass assembly 11 is assembled therein as disclosed in Fig. 5, the packing materials 16 also being utilized to resiliently grip and position the glass assembly 11 in 15 the frame assemblies.

15 The plungers 47 are now slidably moved outwardly so that the shoulder portions 51 engage the holes 53 and the screws 61 will be clamped in place to further secure the frame 38 to the 20 side members 3 and 4 of the frame assembly.

25 The same procedure is followed with the frame assembly C with the exception that the frame assembly C is inverted when the frame assembly C has slidably moved downwardly to its position against the frame member 68, as disclosed in Fig. 2, the overhanging or offset portion 41 contacting the upper surface of the offset portion 39 of the frame 38 of the frame assembly B, thus providing close engagement between the frame 30 assemblies B and D and preventing any infiltration of air, etc., therebetween.

35 If my window mechanism is first used in conjunction with the glass assembly 11, used as for instance during the cold seasons of the year, the glass assembly 11 will be readily removed and replaced by the screen assembly 12 during the warmer seasons of the year, both glass assembly 11 and the screen assembly 12 utilizing the same frame assemblies and structure for their alternate use, said glass assembly 11 and screen assembly 12 being readily removable and replaceable without further removing the frame assemblies A and C from their assembled positions in the channel portions 24 and 25 of the guide members 23.

40 I claim:

1. In a window mechanism for use with the conventional window structure of a building, said window structure being provided with a pair of 45 openings in its side members, the combination of a plurality of pairs of guide members secured at the sides of the window structure and each provided with a pair of channel portions having 50 openings in alignment with said openings in said side members of the window structure, a plurality of pairs of end frame members slidably mounted in said channel portions of said guide members, each of said end frame members being provided with telescopically mounted U-shaped end portions together with side portions 55 extending substantially at right angles to said U-shaped end portions and forming U-shaped portions, a plurality of pairs of side members each provided with U-shaped portions telescopically mounted within an open end of one of said side portions of a pair of said end frame members, a handle member secured to each of said end frame members and each provided with an extension portion, resilient members mounted 60 around said extension portions of and between said handle members of each pair of said end frame members and exerting a thrust to force each of said pair of end frame members outwardly to adjustably engage said channel portions of 65 said guide members, means for adjustably securing

70 ing a pair of said side members to said side portions of each pair of said end frame members, packing materials secured to the inside surfaces of the U-shaped portions of said end frame and said side members and adapted to engage and position glass or screen members, said U-shaped portions having resilient characteristics to force said packing materials to clamp said glass or screen members when inserted between the flange portions of said U-shaped end and side members, a pair of end frame members provided with 75 resilient U-shaped portions adapted to telescopically mount within said U-shaped portions of said side members and each provided with offset portions adapted to engage one another at the central portion of the window structure, packing materials secured to the inside surfaces of said U-shaped portions of said last mentioned pair of end frame members and adapted to engage and position glass or screen members, plunger members 80 movably mounted in said last mentioned pair of end frame members and each provided with portions extending into and engaging said openings of said side members and said window structure, and glass or screen members mounted between said packing materials and the flanges of said U-shaped portions of said end frame and said side members.

2. In a window mechanism, the combination of 85 guide members, frame members slidably mounted in said guide members and provided with resilient flange portions adapted to receive a glass or screen member therebetween, said frame members telescopically engaging one another, resilient means supported by said frame members and adapted to exert an outward thrust on said frame members to adjustably position them in said guide members, and glass or screen members supported between said resilient flange portions of 90 said frame members.

3. In a window mechanism for a window opening, the combination of oppositely disposed frame members, handle members on said frame members, resilient members supported on and extending between said handle members and exerting a thrust to adjustably move said oppositely disposed frame members outwardly to fit 95 window openings of different sizes, and a window member supported in said oppositely disposed frame members and extending across the window opening.

4. In a window mechanism for a window opening, the combination of a frame assembly comprising portions telescopically mounted relative to one another to provide adjustment and each provided with U-shaped flanges, the U-shaped flange of one of said portions being provided with flanges formed at its edges and extending around the edges of the other of said portions to retain 100 said portions against movement in a plane extending substantially at right angles to the plane of telescopic movement of said portions, means for positioning said portions in their adjusted positions, and a window member supported between said U-shaped flanges of said portions and extending across the window opening.

5. In a window mechanism, the combination of 105 guide members, frame members slidably mounted in said guide members and provided with oppositely disposed clamping portions adapted to receive a glass or screen member therebetween, resilient means supported by said frame members and adapted to adjustably move said frame members apart, and glass or screen

members supported between said clamping portions of said frame members.

6. In a window mechanism for a window opening, the combination of oppositely disposed frame members each provided with a flange telescopically engaging the flanges of the other of said frame members, resilient members supported adjacent the sides of said flanges of said frame members and adapted to move said frame members apart to fit window openings of different sizes, and a window member supported in said frame members and extending across the window opening.

7. In a window mechanism adapted to alternately use screen and glass members therein, the combination of a pair of frame members each comprising oppositely disposed flange members for holding said screen and glass members therebetween, means for adjustably positioning said frame members to and from one another to fit windows of different sizes, and means for locking said frame members in adjusted positions, said last mentioned means extending through one side only of said oppositely disposed flange members of one of said pair of frame members to engage one only of said oppositely disposed flanges of the other of said pair of frame members, said screen and glass members extending across the inner ends of said means.

8. In a window mechanism, the combination of frame members suitably mounted and provided with oppositely disposed flanges for receiving a window member therebetween, resilient means suitably mounted and adapted to move said frame members apart, and a window member supported between said oppositely disposed flanges of said frame members.

9. In a window mechanism for a window opening, the combination of a frame assembly provided with side members adjustably connected together to facilitate fitting windows of different widths, said frame assembly being further provided with an end member slidably mounted in said side members, said end member having a fixed length, and a window member supported in said frame assembly and extending across said window opening.

10. In a window mechanism for a window opening, the combination of a frame assembly provided with side members adjustably connected with each other together with an end member of fixed length slidably mounted in said side members, a window member supported in said frame assembly and extending across said window opening, and a plunger member slidably mounted in said end member and adapted to engage side portions of said window opening.

11. In a window mechanism for a window opening, the combination of a frame assembly slidably mounted and provided with means for adjusting it to windows of different sizes, said frame member being further provided with an end portion removably mounted therein and having a fixed length, said end portion being provided with slots in its outermost wall portion, plunger members slidably mounted in said end portion and adapted to engage side portions of said window opening, and handle members supported by said plungers and extending through said slots of said end portion.

12. In a window mechanism, the combination of a frame assembly comprising side and end members provided with means for adjusting said frame assembly to said windows of various sizes, said frame assembly further comprising an end

member having a fixed length, said end member being mounted in said side members to permit removal therefrom when said side members are assembled in the window, and a glass or similar member supported in said side and end members. 5

13. In a window mechanism, the combination of a frame assembly comprising a pair of end members each provided with side channel portions together with end channel portions extending substantially at right angles to said side 10 channel portions, said end channel portions telescopically engaging one another, said frame assembly further comprising channel members forming sides of the frame assembly and telescopically engaging said side channel portions of 15 said end members, said frame assembly further comprising a sole end member having a fixed length and a channel portion entering open ends of said side channel portions of said channel members forming sides of the frame assembly, 20 said last mentioned end member being adapted for removal from the frame assembly to permit removal of a glass or screen member from the channel portions of the frame assembly, and a glass or screen member supported in the channel 25 portions of the frame assembly.

14. In a window mechanism for a window opening, the combination of a pair of end frame members telescopically mounted relative to one another, each of said end frame members being 30 provided with side portions fixedly secured thereto, a pair of side frame members each telescopically mounted relative to one of said side portions of said end frame members and provided with open end portions, a lower sash member 35 engaging the open end portions of said side frame members and forming an end frame member of the window mechanism, said lower sash member constituting a sole member extending between the open end portions of said pairs of side 40 frame members, and a glass or screen member supported in said end frame members, said side frame members and said lower sash member.

15. In a window mechanism for a window opening, the combination of an end member assembly 45 comprising a pair of members telescopically mounted relative to one another, a pair of oppositely disposed side members each telescopically mounted relative to one of said pair of members comprised by said end member assembly, an end 50 member oppositely disposed to said end member assembly and comprising a sole member engaging and extending between end portions of said side members, and a window member supported in said end member assembly, said pair of side 55 members and said last mentioned end member.

16. In a window mechanism, the combination of two end frame members and two side frame members forming an end and side portions of the window mechanism, each of said frame members being provided with oppositely disposed flanges adapted to clamp a window member therebetween, each of said frame members being adjustably connected to its adjacent frame member to permit adjustable movement longitudinally 65 of the end and side portions of the window mechanism, a sole third end frame member forming an end portion of the frame of the window mechanism and engaging open end portions of said two side frame members, said sole third end 70 frame member being provided with oppositely disposed flanges adapted to clamp said window member, and a window member extending between and supported by said oppositely disposed flanges of all of said frame members. 75

17. In a window mechanism, the combination of a frame assembly comprising a pair of end frame members telescopically mounted relative to one another to form an end portion of the frame assembly, said frame assembly further comprising a pair of oppositely disposed frame members each telescopically mounted relative to one of said pair of end frame members and forming side portions of the frame assembly, said frame assembly being further provided with a sole frame member engaging the ends of each of said pair of oppositely disposed frame members and forming an end portion of the frame assembly, each of said frame members comprised by said frame assembly being provided with oppositely disposed flanges, and a window member supported between said oppositely disposed flanges of said frame members.
18. In a window mechanism, the combination of a frame assembly comprising a plurality of pairs of frame members forming side and an end portions of the frame assembly, each of said pair of frame members being adjustably mounted relative to one another and forming a side or end portion of the frame assembly, a sole frame member connected with said plurality of pairs of frame members and forming an end portion of the frame assembly, and a window member supported by and extending between said frame members.
19. In a window mechanism for a window opening, the combination of adjustable frame mem-
- bers forming three side portions of a frame assembly, a frame member of fixed length and engaging said first mentioned members to form a fourth side portion of said frame assembly, and plunger members mounted in said last mentioned frame member and provided with portions adapted to engage portions of said first mentioned frame members to maintain them in spaced positions.
20. In a window mechanism for a window opening, the combination of adjustable frame members forming three side portions of a frame assembly, a frame member of fixed length and engaging said first mentioned members to form a fourth side portion of said frame assembly, and plunger members mounted in said last mentioned frame member and provided with portions adapted to engage portions of said first mentioned frame members to maintain them in spaced positions, and handle means connected to said plunger members and adapted to lock them in a fixed position for spacing said portions of said first mentioned frame members.
21. In a window mechanism for a window opening, the combination of a frame assembly comprising side portions adjustably connected, resilient means mounted to adjustably expand said frame assembly to fit window openings of different sizes, and a window member supported by said frame assembly and extending between its side portions.

FRANK E. ZICK.
